R. M. MUELLER,
AIR TRAP GASOLINE STRAINER.
APPLICATION FILED NOV. 24, 1919.

1,427,619.

Patented Aug. 29, 1922.

UNITED STATES PATENT OFFICE.

ROBERT M. MUELLER, OF NEW YORK, N. Y.

AIR-TRAP GASOLINE STRAINER.

1,427,619.

Specification of Letters Patent. Patented Aug. 29, 1922.

Application filed November 24, 1919. Serial No. 340,178.

To all whom it may concern:

Be it known that I, ROBERT M. MUELLER, a citizen of the United States, residing at New York, in the county of New York and State of New York, have invented certain new and useful Improvements in Air-Trap Gasoline Strainers, of which the following is a specification.

This invention relates to straining devices for removing sediment from gasoline and more particularly relates to a gasoline strainer for automobiles.

One important object of the invention is to improve the general construction of devices of this character.

A second important object of the invention is to provide an improved form of gasoline strainer for automobiles, so arranged that the ordinary running of the automobile will act to keep the strainer element from clogging.

A third important object of the invention is to so improve devices of this character that there will always be a certain amount of air above the gasoline in the strainer chamber whereby the gasoline may move freely about in such chamber and thus wash the face of the strainer element.

With the above and other objects in view, as will be hereinafter apparent, the invention consists in general of certain novel details of construction and combinations of parts hereinafter fully described, illustrated in the accompanying drawings and specifically claimed.

In the accompanying drawings, like characters of reference indicate like parts in the several views, and

Figure 1 is a front elevation of the improved device,

Figure 2 is a section on the line 2—2 of Figure 1,

Figure 3 is a section on the line 3—3 of Figure 2.

In the embodiment of the invention shown, and which is to be taken as merely a typical form, there is provided a casing 10, preferably having a glass front 11. In the bottom of this casing is a clean out plug 12, provided with a central pipe threaded opening 13, wherein may be fitted a pet cock or plug as desired. Extending downward through the top of the casing and terminating at a point just above the center of the casing is an inlet pipe 14, while a similar outlet pipe 15 extends upward through

the top from a point on a level with the end of the inlet pipe 14. Screwed on or otherwise secured to the outlet pipe 15 is a plate 16 from which depends a strainer 17, extending well below the mouth of the outlet pipe and also well above said mouth.

By reason of this arrangement, the upper part of the chamber within the casing acts as an air chamber since the normal level of the gasoline can rise but little above the mouth of the inlet and outlet pipes. Consequently, when the device is installed on an automobile between the tank and the carburetor, and the machine is running, the gasoline in the lower part of the casing will wash around in the casing, thus setting up currents across the faces of the strainer proper and preventing the accumulation of sediment on such faces with its attendant result of clogging the strainer and choking or preventing the flow of gasoline therethrough.

There has thus been provided a simple and efficient device of the kind described and for the purpose specified.

It is obvious that minor changes may be made in the form and construction of the invention without departing from the material principles thereof. It is not, therefore, desired to confine the invention to the exact form herein shown and described, but it is wished to include all such as properly come within the scope claimed.

Having thus described the invention, what I claim as new is:

1. In a device of the kind described, a casing forming a strainer chamber, an inlet pipe extending downward from the top of the casing and terminating slightly above the center of the casing, an outlet pipe extending upward through the casing from the level of the end of the inlet pipe, a plate carried by the outlet pipe, a strainer carried by the plate and surrounding the mouth of the outlet pipe, and a cleaning plug in the bottom of the casing.

2. In a device of the character described comprising a casing, an inlet and an outlet pipe in communication with said casing having the outlet and inlet ends of said respective pipes terminating in a common plane slightly above the center of the casing, and a drain in the bottom of said casing.

3. In a device of the character described comprising a casing, an inlet and an outlet pipe in communication with said casing having the outlet and inlet ends of said respec-

tive pipes terminating in a common plane slightly above the center of the casing, a filtering means associated with the outlet pipe about the inlet end thereof, and a drain in the bottom of said casing.

4. In a device of the character described comprising a casing, an inlet and an outlet pipe in communication with said casing having the outlet and inlet ends of said respective pipes terminating in a common plane slightly above the center of the casing, a strainer mounted on the outlet pipe and extending above and below the inlet end

thereof, and a drain in the bottom of the casing.

5. A gasoline filtering device comprising a sealed casing, means for maintaining a constant level of gasoline within said casing below the top thereof consisting of an inlet and an outlet pipe terminating in a common plane slightly above the center of the casing, a strainer between the terminal ends of said pipes within the casing, and a cleaning plug in the bottom of said casing.

In testimony whereof I affix my signature. 25
ROBERT M. MUELLER.
